COMBINATION JACK

Austin O. Middlemiss, Portland, Oreg.

Application May 31, 1929. Serial No. 367,285

1 Claim. (Cl. 254—103)

This invention relates to jacks of the mechanical type. The object of the invention is to produce a jack, efficient in operation by being both simple and geared, combining strength and lightness and also compactness in proportion to the lift. A further object of the invention is a construction so designed that the jack is automatically protected from lifting too far and disengaging the screw threads. These and other features will be apparent by a study of the accompanying drawing and specifications.

Fig. 1 is a side elevation of the jack and cross sections.

Fig. 2 is a top view.

Referring to these views, the part details are as follows: I is the base; A is the screw bolted to the base; B is a sleeve or nut which is fitted to turn on part A; part C is a gear housing holding the gears and fitted to allow relative rotation 20 of part B but rising with it; part H is hinged at K and can be placed parallel to the axis of the screw or turned down as shown by the arrow. When the part H is out of the part C, part C and the part B which is locked to part C by the gearing 25 may be rotated by a bar placed in the bosses O. This makes it possible for the jack to operate as a simple screw jack. H is a pivotally mounted housing restraining member. When part H engages part C, and suitable turning means are used

on part F, the part B is revolved with the gearing with great power through the worm P, the worm wheel E which is integral with gear D, gear D turns gear N which is integral with the nut B.

After part C has risen to a point such that it 63 clears member H, further rotation of the part F will cause the entire gear train to rotate with relation to the base I and the sleeve B. The sleeve B therefore fails to rotate and becomes automatically inoperative as a geared jack, leaving 65 a safe amount of threads engaged.

The top is shown as a spherical seat on the part B, Q is a washer, N is a spring and M is a screw.

Special attention is called to this construction, which makes it possible to make the part B 70 thick around the central hole and makes the oscillating top L tend to return to center.

Having thus clearly described my invention, what I claim is:

In a jack of the class described, the combination of a base with a screw attached, a threaded sleeve fitted to the screw, a gear housing surrounding the sleeve, hollow projecting bosses on the housing, a geared drive comprising a worm wheel and a worm embraced by the housing and a restraining member coacting with a notch in the housing of limited height and pivotally attached to the base member.
